UNITED STATES PATENT OFFICE

2,064,167

NONREFILLABLE BOTTLE

Joseph Scott Junkin, Chicago, Ill.

Application December 7, 1935, Serial No. 53,288

1 Claim. (Cl. 215—83)

The invention relates to improvements in non-refillable bottles and has for its object the provision of an improved construction of this character so constructed and arranged as to prevent ready refilling of the bottle with spurious liquid.

Other objects will appear hereinafter.

The invention consists in the combinations and arrangements of parts hereinafter described and claimed.

The invention will be best understood by reference to the accompanying drawing forming a part of this specification, and in which

Fig. 1 is a top plan view of a bottle embodying the invention;

Fig. 2 a side view of the neck portion thereof;

Fig. 3 a vertical section through the neck portion of the bottle; and

Fig. 4 a horizontal section taken substantially on line 4—4 of Fig. 2.

The embodiment of the invention illustrated in the drawing comprises a bottle body 10 of conventional form and having a neck portion formed of separate lower and upper portions 11 and 12. The upper portion 12 is permanently closed at the top and preferably made square in horizontal section as shown. At the juncture between said neck portions they both are outwardly enlarged and provided with recesses 13, each recess being provided with three divergent grooves or notches 14 for interlocking with the sealing band 15. The sealing band 15 is made of soft metal pressed into the recesses 13 and 14, so as to interlock therewith and join the upper portion 12 of the neck to the lower portion 11 thereof.

A cutting element 16 in the form of a steel strip V-shape in cross section is embedded as indicated in the inner periphery of the band 15, one end 17 of said strip protruding as shown and provided with a ring 18 for engagement by the finger. At its other end the strip 16 is provided with an outwardly turned end 19 embedded in the band 15, as best shown in Fig. 4, and whereby said end of said strip is anchored to prevent longitudinal slippage in the band 15. A cork 20 is arranged as shown in the neck of the bottle to traverse the band 15.

By this arrangement a bottle is provided in which the contents will be sealed until the band 15 is severed. To sever the band 15, the ring 18 is engaged by the finger and the cutting strip

16 drawn outwardly through the band 15, thereby severing the same. This cutting action of the strip 16 is facilitated by its V shape and also by the anchoring of its inner end 19 in the strip 15. The square shape of the top of the neck 12 also facilitates the gripping thereof during the severing manipulation. When the band 15 has thus been severed, the bottle may be opened by twisting the top 12 and thus removing the lower portion of the cork 20 from the lower portion of the neck 11. After a portion of the contents of the bottle have been removed, the same may be sealed by re-inserting the lower end of the cork 20 in the neck portion 11, the combined top portion 12 and cork portion 20 thus serving as a removable stopper for the bottle as and when desired.

The band 15 is preferably made of a soft metal which may be readily incorporated in the neck of the bottle by pressure and will subsequently solidify or crystallize so as to hold the bottle neck in proper form and position and thus become a part and parcel of the bottle itself. When the cutting strip 16 is withdrawn, the band 15 is shattered, leaving fragments sticking in the recesses in the neck so as to render it practically impossible to refill the bottle so as to deceive the purchaser into believing he is receiving the original package.

While I have illustrated and described a preferred form of construction for carrying my invention into effect, this is capable of variation and modification without departing from the spirit of the invention. I therefore do not wish to be limited to the precise details disclosed but desire to avail myself of such variations and modifications as fall within the scope of the appended claim.

I claim:

A bottle provided with a neck permanently sealed at its top, the upper portion of said neck being separated from the lower portion thereof, there being comparatively large and shallow recesses in the opposed edges of said neck and each of said recesses being provided with divergent notches; a soft band of locking substance interposed between said neck portions and pressed into and interlocking with said recesses and notches; and a cork in said neck traversing said band.

J. SCOTT JUNKIN.
